GOLF GAME BOARD

James T. Reese, 5350 Meadowlark Drive NW,
North Canton, Ohio 44720

Filed Oct. 24, 1973, Ser. No. 409,061

Term of patent 14 years

Int. Cl. D21—01
U.S. Cl. D34—5 GL

FIG. 1

FIG. 7

FIG. 6

FIG. 5

FIG. 2

FIG. 3

FIG. 4

FIG. 1 is a perspective view of the golf game board showing my new design;

FIG. 2 is a top plan view thereof;

FIG. 3 is an enlarged fragmentary sectional view taken on line 3-3, FIG. 2;

FIG. 4 is an enlarged fragmentary sectional view taken on line 4-4, FIG. 2;

FIG. 5 is an enlarged fragmentary sectional view taken on line 5-5, FIG. 2;

FIG. 6 is an enlarged fragmentary sectional view taken on line 6-6, FIG. 2; and

FIG. 7 is an enlarged fragmentary sectional view taken on line 7-7, FIG. 2.

I claim:

The ornamental design for a golf game board, as shown.
